US0D1084241S

(12) **United States Design Patent** (10) **Patent No.:** **US D1,084,241 S**
(45) **Date of Patent:** **** Jul. 15, 2025**

(54) **MESH GUTTER COVER**

(71) Applicant: **E-Z Products LLC**, St. Clair, MO (US)

(72) Inventor: **James E. Ealer, Sr.**, St. Clair, MO (US)

(73) Assignee: **E-Z PRODUCTS LLC**, St. Clair, MO (US)

(**) Term: **15 Years**

(21) Appl. No.: **29/789,232**

(22) Filed: **Sep. 10, 2021**

Related U.S. Application Data

(63) Continuation of application No. 17/343,555, filed on Jun. 9, 2021, now Pat. No. 11,591,801.

(51) **LOC (15) Cl.** **23-01**

(57) **CLAIM**

The ornamental design for a mesh gutter cover as shown and described.

DESCRIPTION

FIG. 1 is a perspective view of a mesh gutter cover;

FIG. 2 is a front view thereof;

FIG. 3 is a top view thereof;

FIG. 4 is a right side view thereof;

FIG. 5 is a rear view thereof;

FIG. 6 is a bottom view thereof; and,

FIG. 7 is a left side view thereof.

1 Claim, 7 Drawing Sheets
